CLAIM

The ornamental design for a cooking basket, as shown and described.

DESCRIPTION

FIG. 1 is a perspective view of a cooking basket showing
my new design;

FIG. 2 is a front elevational view thereof, the opposite side being a mirror image;

FIG. 3 is a top plan view thereof;

FIG. 4 is a bottom plan view thereof; and

FIG. 5 is a front elevational view of a second embodiment of that shown in FIG. 1.

FIG. 1

FIG. 2

FIG. 4
